UNITED STATES PATENT OFFICE.

NILS ERIK WAHLBERG, OF PONTIAC, MICHIGAN.

COMBINED ROTARY AND SLIDE VALVE FOR EXPLOSION-ENGINES.

1,197,412

Specification of Letters Patent.

Patented Sept. 5, 1916.

Application filed May 4, 1912. Serial No. 695,063.

To all whom it may concern:

Be it known that I, NILS ERIK WAHLBERG, a subject of the Czar of Russia, residing at Pontiac, in the county of Oakland and State of Michigan, one of the United States of America, have invented certain new and useful Improvements in Combined Rotary and Slide Valves for Explosion-Engines, of which the following is a specification, reference being had therein to the accompanying drawings.

The invention relates to explosion engines and more particularly to that type in which the ports are controlled by a sliding sleeve valve in concentric relation to the piston and cylinder. With engines of this type it has been found desirable to provide two sleeves in order to obtain a quick opening of the ports in properly timed relation, but this considerably increases the cost of construction. With the present invention I avoid the use of the second sleeve by combining with the single sleeve valve, a rotary valve which controls the same ports and which is arranged to close said ports during the compression and explosion strokes. This will effectively seal the explosion chamber as the rotary valve acts in coöperation with the rings on the piston and cylinder head. On the other hand, during the exhaust and intake strokes where part of the rotary valve is open there will be but slight leakage of gas due to the low pressure. I further simplify the construction by utilizing the rotary valve as an eccentric shaft for operating the reciprocating sleeve to which it is connected by a rod or pitman.

The invention therefore, consists in these and other features of construction as hereinafter set forth.

In the drawings,—Figure 1 is a vertical cross section through an engine provided with my improved valve construction; Fig. 2 is a side elevation partly in longitudinal section.

A is the cylinder of the engine which may be either single or of the multi-cylinder block type, B is the crank case, C are the pistons within the cylinders, and D is the reciprocating sleeve which is arranged intermediate the piston and cylinder.

At one side of the cylinder is arranged a valve case E containing a rotary valve F of the cylindrical type. The ports G of this valve are adapted to alternately register with inlet and exhaust ports G' and H and

to connect the same with a port I which is controlled by the sleeve D. The valve F is driven by any suitable drive mechanism such as the spiral gears I', vertical shaft J and spiral gears K which communicate movement of the crank shaft to the valve.

The sleeve D is driven through the medium of the rotary valve and to this end said valve is formed with eccentric grooves L therein forming eccentric bearing pins M which are engaged by pitman rods N, the lower ends of which extend into the crank case and are pivotally connected at O to the sleeve D. These eccentric bearings are preferably arranged upon opposite sides of the ported portion of the valve and are engaged by a bifurcated pitman rod. The pins M being within the periphery of the body of the valve permit of inserting said valve endwise through the case E, and when in position the pitman is engaged therewith by providing split bearings N' therefor.

With the construction described the rotary valve is driven through the gears I' and K and shaft J from the crank shaft of the engine and the eccentric pins M and rods N communicate reciprocatory movement to the sleeves D. All of the parts of the drive mechanism can be inclosed and I preferably form a manifold O' for the inlet and exhaust integral with the cover plate P which incloses the chambers in which the rods N are located.

What I claim as my invention is:

1. The combination with a ported engine cylinder, of a slide valve and a rotary valve coöperating to control a port in said cylinder, a timed drive mechanism for said rotary valve, an eccentric bearing on said rotary valve, and a pitman rod engaging said eccentric bearing and connected to said slide valve to reciprocate the same.

2. The combination with a ported cylinder, of a cylindrical sleeve valve, and a rotary valve coöperating to control a port in said cylinder, a timed drive mechanism for said rotary valve, an eccentric bearing on said rotary valve, and a pitman engaging said eccentric bearing and pivotally connected with said sleeve valve.

3. The combination with a ported engine cylinder, of a sleeve valve concentric with said cylinder, a rotary valve controlling a port of said cylinder in coöperation with said sleeve valve, eccentric bearings upon

2
opposite sides of the ported portion of said rotary valve, a timed drive mechanism for said rotary valve, and a bifurcated pitman embracing the ported portion of said rotary valve and engaging said eccentric bearings, the opposite end of said pitman being pivotally connected with said sleeve valve.

4. The combination with a ported engine cylinder, of a slide valve and rotary valve 10 coöperating to control said port, pins within the periphery of the body of the rotary valve, a timed drive mechanism for said rotary valve, an eccentric bearing on said rotary valve, and a pitman rod engaging said eccentric bearing, split bearings being provided therefor, said pitman rod being connected with the slide valve.

5. The combination with a ported engine cylinder, of a slide valve and a rotary valve 15 having its axis prependicular to the axis of the said cylinder, said slide valve and rotary

valve controlling a port of said cylinder in coöperation, and a direct connection between said slide valve and rotary valve for operating one through the medium of the other. 25

6. The combination with a ported engine cylinder, of a slide valve and a rotary valve 30 coöperating to control a port in said cylinder, said rotary valve having its axis transverse to the axis of said cylinder, a timed drive mechanism for said rotary valve, an eccentric bearing on said rotary valve, and a pitman rod engaging said eccentric bearing and connected to said slide valve to reciprocate the same. 35

In testimony whereof I affix my signature in presence of two witnesses.

NILS ERIK WAHLBERG.
